UNITED STATES PATENT OFFICE.

ALFRED W. F. GUEST, OF BROOKLYN, NEW YORK, ASSIGNOR TO MERGENTHALER LINOTYPE COMPANY, A CORPORATION OF NEW YORK.

TYPOGRAPHICAL MACHINE.

1,277,571.

Specification of Letters Patent.

Patented Sept. 3, 1918.

Application filed July 15, 1916. Serial No. 109,452.

To all whom it may concern:

Be it known that I, ALFRED W. F. GUEST, a citizen of the United States, residing at Brooklyn, in the county of Kings and State 5 of New York, have invented certain new and useful Improvements in Typographical Machines, of which the following is a specification, reference being had therein to the accompanying drawing.

10 My invention relates to typographical machines, such as linotype machines of the general organization represented in United States Letters Patent to O. Mergenthaler, No. 436,532, wherein circulating matrices are 15 released from a magazine in the order in which their characters are to appear in print and then assembled in line, the composed line transferred to the face of a mold, the mold filled with molten metal to form a slug 20 or linotype against the matrices which produce the type characters thereon, and the matrices thereafter returned through distributing mechanism to the magazine from which they started. More particularly, it 25 relates to machines of the kind disclosed in the Letters Patent of D. S. Kennedy, Nos. 1,193,558 and 1,193,559, and his pending application Serial No. 52,999, and other of his patents and applications unnecessary to 30 refer to herein.

In these machines, the matrices are stored according to font in a plurality of magazines, each provided with its own series of escapements which effect the discharge of 35 the contained matrices in the required order. The several series of escapements are controlled by a common set of actuating reeds, which tend to actuate the corresponding escapements of all the series at each operation; 40 but such simultaneous actuation of the escapements is prevented by locking devices, one for each series, which are controlled by magazine selecting keys in such manner that when one locking device is moved to inactive 45 position, the others are simultaneously restored to active position, thus permitting the delivery of matrices from one magazine only at a time. Further, in these machines, the escapement actuating reeds are carried 50 by a frame or so-called "front plate," which is pivotally supported so as to be swung forwardly to give access to the interior parts, this movement of the frame at the same time disconnecting the actuating reeds from 55 the escapements. Means are also provided,

when or before the frame is thus swung forwardly, for restoring the escapement locking devices to active position in order to prevent the release of matrices from the magazines due to the disconnection of the 60 actuating reeds from the escapements.

It has been found in practice that under certain conditions, an escapement locking device will fail to return to active position, as, for instance, when one of the escapements 65 is caught by a matrix improperly located in the magazine. In such event, the escapements of the series remain unlocked when the actuating reeds are disconnected therefrom, thus allowing the lowermost matrices 70 to escape from the magazine with the evil results which necessarily follow.

It is the object of my present invention to obviate these objections, and to that end I have provided each series of escapements 75 with locking means which will operate in the above circumstances to hold them against action even though one of them occupies an abnormal position at the time. In one of the embodiments illustrated, I have modified 80 the escapements and their key-controlled locking devices so that the latter may be moved to active position notwithstanding the abnormal location of one or more of the escapements; and in another embodiment, 85 I have provided each series of escapements with a supplemental locking device which will serve to hold them in locked condition in the event that the usual key-controlled locking device fails to act. In this latter 90 embodiment, means are provided whereby the supplemental locking devices are moved to active position automatically when or before the front plate is moved. In this way the locking of the escapements is insured at 95 all times, and even though one of them should be caught by an offending matrix.

In the accompanying drawings I have illustrated my improvements merely in preferred form and by way of example, and 100 obviously many changes and variations may be made therein which will still be comprised within the spirit of my invention. Generally speaking, I desire it to be understood that I do not limit myself to any 105 specific form or embodiment, except in so far as such limitations are specified in the claims.

Referring to the drawings:

Figure 1 is a vertical section through a 110

portion of a linotype machine of the kind described above, showing my invention applied thereto;

Fig. 1^a is a similar view taken through 5 the magazines and their selecting mechanism;

Fig. 1^b is a section on the line 1^b—1^b of Fig. 1^a;

Fig. 2 is a view similar to Fig. 1 with 10 some of the machine elements omitted and showing the parts in different position;

Figs. 3, 4, 5 and 6 are detail-views illustrating diagrammatically different stages in 15 the operation of the supplemental locking device, Fig. 3 being a section on the line 3—3 of Fig. 1, and Fig. 4 a section on the line 4—4 of the same figure;

Figs. 7, 8 and 9 illustrate an alternative construction, the first two figures being de- 20 tails in vertical section, and the last a section on the line 9—9 of Fig. 7; and

Figs. 10 and 11 illustrate a modification 25 of my invention, Fig. 10 being a vertical section similar to Fig. 1, and Fig. 11 an enlarged detail.

As my improvements have been embodied in a machine of the kind disclosed in the Kennedy application, Serial No. 52,999, before referred to, I have confined the drawings to such parts thereof as are immediately concerned. If desired, reference may be had to said application for a further and complete illustration and description of the remainder of the machine.

Referring to Fig. 1, the matrices X are stored according to font in one or the other of the magazines B, only two of which are shown, but of which a greater number might be employed if desired. The matrices are 30 released from their corresponding magazine by the escapements C and pass through one or the other of the throats D¹ into the vertical channeled raceway D whence they are carried to the assembler and composed 45 in line in the customary way.

The escapements C are of the usual construction, each comprising a rocking lever and a pair of pawls, which latter are projected alternately into the corresponding 50 magazine channel to control the release of the contained matrices. The escapements for each magazine are supported in series in the bar or frame C⁸, which may be connected directly to the magazine, or, (as in the Kennedy application) pivotally secured to the magazine base-frame. The escapements of both magazines are controlled by the single series of actuating members or reeds C² formed with the rearward pro- 60 jection C¹¹ overlying the forward arms of the small levers C⁴, pivoted to the escapement supporting frames C⁸, and which under the influence of the members C² act to rock the corresponding escapements of the 65 two magazines simultaneously in one direc-

tion against the force of the springs C⁴ tending to rock them in the opposite direction.

Attached to the lower ends of the actuating members C² are the spring C³ pulling 70 downwardly thereon from a relatively fixed part of the machine and of sufficient strength to overcome the action of the springs C⁴, so as to hold the lowermost pawls of the escapements in engagement with the leading 75 matrices in the magazines, which are thus prevented from escaping therefrom. To permit the release of such matrices, therefore, it is necessary to raise the actuating members C² against the force of their 80 springs C³, when the lighter springs C⁴ will be allowed to act; and this movement of the actuating members is effected by the pivoted levers C⁵ engaging beneath the projections C¹² thereon and arranged to be rocked up- 85 wardly by the vertically guided rods C⁶ operated from the keyboard mechanism in the usual way.

Since the actuating members C² control the escapements of both magazines, their 90 operation would result in the release of matrices from both at the same time were other means not provided. Each series of escapements, therefore, is equipped with the well-known transverse rock shaft H which 95 is rotatably mounted in the supporting frame C⁸ and arranged in proximity to the rear ends of the escapement levers, the shaft being cut away or recessed in the usual way so that in one position it will lock the 100 escapements against operation, while in another position it will permit their operation. The two rock shafts H are provided at one end with crank arms (shown in dotted lines) which are connected by the vertical rods H⁴ to the pivoted levers H⁶ operated through the medium of the rods H⁷ by the cam yokes H⁸ controlled in the usual way by the magazine selecting keys H¹⁰ disposed alongside the main keyboard. The rods H⁴ 110 are constantly urged upward to move their rock shafts H to locking position by the springs H⁵, and are held down against the action of the springs by the hooks H¹² projecting upwardly from the locking plate 115 H¹¹ and adapted to engage over the rear arms of the levers H⁶ when they are rocked downward by the actuation of the corresponding magazine selecting keys (see Figs. 1^a and 1^b). The locking plate H¹¹ is 120 normally held toward the right in Fig. 1^b by the spring H⁹ with the inclined ends of its hooks H¹² in the path of the levers H⁶, so that as one or the other is rocked downward it displaces the locking plate toward the left and passes beyond the corresponding hook, which then immediately snaps across the lever and holds it depressed with the connected rock shaft H in unlocking position. It will be noted that the dis- 130

- placement of the locking plate by one of the levers H^6 releases the other, if the latter had previously been locked down, and consequently permits the connected rock shaft 5 to be returned to its locking position by the spring H^5 . In other words the arrangement is such that the alternate actuation of the two keys H^{10} effects the movement of the rock shafts H to locking and unlocking 10 position alternately, so that but one series of escapements C is allowed to be operated by the actuating members C^2 at a time and consequently matrices released only from the corresponding magazine.
- 15 The escapement actuating members C^2 and the other devices are all mounted upon the pivoted frame or front-plate G , (shown only in part herein) which may be swung outwardly away from the magazines to permit 20 their removal or to give access to the interior mechanism. Before or when this swinging of the frame G is effected, the rock shafts H should be restored to active position, as otherwise (due to the disconnection 25 of the actuating members C^2 from the escapements) the latter would be actuated by the springs C^4 to release the lowermost matrices in the magazines. The means employed to secure this result are the same as illustrated 30 in the above-mentioned Kennedy application Serial No. 52,999, consisting of the long lever H^{13} connected to the locking plate H^{11} and fast to the rear end of the fore-and-aft rock shaft H^{15} , which is provided at its 35 opposite end with the arm H^{16} arranged in position to be engaged by the arm H^{17} secured to one end of the cam bar H^{18} rotatably mounted in the swinging frame G and coöperating with the rearward projections 40 C^{18} on the escapement reeds C^2 , so that when rotated it will raise the latter and disconnect them from the several series of escapements C preparatory to the outward movement of the frame. At its opposite end the cam bar 45 H^{18} (Fig. 2) is provided with an arm H^{30} connected by means of a long link H^{31} to a crank arm H^{32} fast to the stub shaft on which is mounted the operating handle H^{33} provided with the cam or eccentric H^{35} 50 which is adapted to engage a part of the fixed machine frame and lock the swinging frame G in operative position. The lever H^{13} is normally urged toward the left (Fig. 1^b) by the spring H^{14} , which is of sufficient 55 strength to overcome the antagonistic spring H^9 of the locking plate H^{11} and to move the latter to unlocking position. Normally, however, the lever H^{13} is held toward the right by the cam bar H^{18} through the intermediate connections described, so that the spring H^{14} is not allowed to act, but when the cam bar is rotated by the unlocking of the frame G its connections with the lever H^{13} are broken and the latter, therefore, under the influence of the spring H^{14} , is caused 60 to move the locking plate H^{11} to inactive position. The effect of this arrangement is that either rock shaft H , which may be standing in inactive position at the time, will be restored to active position when the frame G is unlocked preparatory to its movement outwardly from operative position. 70
- Fig. 1 shows the parts in a normal position with the swinging frame G locked against movement, and with one of the rock shafts H in inactive position and the other in active position. If, now, it should be desired to draw the frame G forwardly, the operating handle H^{33} is rotated to the position shown in Fig. 2 in the direction of the arrow there indicated, thus unlocking the frame G and through the connection described releasing the rod H^4 connected to the particular rock shaft in unlocking position, (in Fig. 1 the rock shaft for the upper magazine) which is then immediately restored to locking position by the spring H^5 . 80
- The parts so far described and their manner of operation are fully set forth in the aforesaid Kennedy application 52999, and 90 the corresponding parts are indicated by substantially the same letters of reference.
- It may happen that for one reason or another the return of the rock shaft H to active position, as above described, will be prevented, as when it is engaged with an escapement which is caught by a matrix improperly located in the magazine. Thus, in Fig. 1, one of the escapements for the upper magazine is shown as having its lower pawl held out of the magazine by a matrix which has passed beyond its proper location, causing the escapement to occupy an abnormal position, or one which is the reverse 100 of that it should occupy; namely, with the upper end of the escapement lever held close up against the rock shaft H , thus locking it against rotation. Consequently, when the frame G is to be swung forwardly, the release of the rod H^4 fails to restore the connected rock shaft to active position, (the spring H^5 yielding) and the lowermost matrices in the upper magazine may fall out 105 into the machine, since the actuating reeds C^2 are disconnected from the escapements by the unlocking and the movement of the frame, and the escapements are thus allowed to be operated by the springs C^4 . 110
- This difficulty is avoided according to my invention by the provision of a supplemental locking device for each series of escapements, which serves to hold them against action in the event that the rock shaft H fails to do so, and which, preferably, is operated automatically as the frame G is unlocked to 120 be swung forwardly. In the present instance, (see particularly Figs. 2-6) it is in the form of a thin transverse strip or plate c , arranged to coöperate with upstanding lips c^1 on the upper edges of the escapement 125 130

actuating levers C^1 . The plate c is attached to the escapement supporting frame C^8 by means of inclined pin-and-slot connections c^2 , of such character as to cause the plate to be moved edgewise upwardly and downwardly as it is shifted longitudinally to the left and right respectively. A spring c^4 (see Figs. 3 and 4) tends constantly to hold the plate in its leftmost position, where it will stand (as shown in Fig. 1) some distance above the lips c^1 on the pivoted levers C^1 , which may thus be operated freely. When, however, the plate is shifted to the right, its lower edge is brought down into engagement with the lips c^1 and locks the levers C^1 against rotation (as shown in Fig. 2), the plate being held in this position by a spring-actuated detent c^8 , which is seated in a recess in the escapement frame and is provided at its forward end with a reduced portion c^9 adapted to pass through a hole or opening c^{11} in the locking plate. The locking of the actuating levers C^1 , due to their engagement with the escapements, consequently locks the latter in their normal position against the action of the springs c^4 . To release the parts, it is merely necessary to disengage the detent, it being provided with a projecting pin c^{10} for this purpose.

The shifting of the plates c to the right is effected by means of small latches c^5 pivoted to bracket plates c^6 , one of which is secured to the inside face of the long link H^{31} , and the other to an upward and rearward extension H^{34} thereof. The link H^{31} , it will be remembered, constitutes a part of the connections between the locking means for the swinging frame G and the locking devices which hold the rock shafts H in inactive position, the connections being such that the link is moved upwardly and downwardly as the frame G is unlocked and locked respectively. The upward movement of the link H^{31} , thus effects the raising of the latches c^5 , which, by their engagement with the left ends of the locking plates c , (which are beveled or inclined at such ends) shift or cam the plates to the right against the action of the springs c^4 . Thus, the parts normally occupy the position shown in Figs. 3 and 4, with the plate c located to the left and with its inclined end overlying the latch c^5 . When now the latch is moved upwardly, it engages the beveled end of the plate and shifts it to the right, as illustrated in Fig. 5, this movement of the plate also causing it to be depressed edgewise into engagement with the pivoted levers C^1 , where it is held by the detent c^8 (see Fig. 2).

In other words, the operation of the supplemental locking devices is effected by the unlocking of the swinging frame G , so that when the latter is swung forwardly the escapements will surely be held against action. Before the frame G is restored to its

operative position, the detents c^8 are disengaged from the locking plates by means of the protruding fingers c^{10} , so as to allow the plates to resume their normal inactive positions to the left. When so located, however, the plates would stand beneath the latches c^5 and interfere with the downward movement of the arm H^{31} , which takes place when the frame G is locked or relocked in place. For this reason, each latch is arranged to yield upwardly, (see Fig. 6) as the arm H^{31} is depressed, the latch thus being free to pass the locking plate and thereafter to fall back into its horizontal position beneath the inclined end thereof.

The operation of the parts will have been understood from the foregoing description. Ordinarily, when the front plate is swung forwardly, the rock shafts H are returned to active position, and in such event, the escapements are locked by two different instrumentalities. It may happen, however, that the rock shafts H cannot return to their active position, as when one of the escapements is caught in the manner illustrated in connection with the upper series in Figs. 1 and 2, and in such event the supplemental locking device serves alone to hold the escapements against action. In this connection, it will be noted that the locking plate is free to be moved to its active position even though one of the escapements should be caught. For instance, as shown in Fig. 1, when one of the escapements is caught, the upstanding lip c^1 on the corresponding actuating lever C^1 is located to one side of the locking plate and out of its path of movement, so that it may pass therebeyond and into locking engagement with the upstanding lips on the remaining actuating lever, as illustrated in Fig. 2.

The effect of the above arrangement, therefore, is that the escapements will always be locked against action whenever the frame G is swung forwardly from its operative position. The locking of the escapements indirectly results in the locking of the matrices in the magazine, so that, more broadly speaking, the effect is that the escape of the matrices from both magazines is always prevented when the frame G is moved.

Figs. 7, 8 and 9 illustrate an alternative construction wherein the supplemental locking devices are controlled entirely automatically, means being provided for shifting them both to active and inactive position as the frame G is unlocked and locked, respectively. It will be noted that the plates c are still retained, being connected to the escapement supporting frames as before by pin-and-slot connections, by means of which they are moved edgewise when shifted longitudinally. In this instance, however, the slots are inclined in a direction opposite to

that shown in the first form so as to cause the plates to move downwardly instead of upwardly as they are shifted to the left, and to move upwardly instead of downwardly as they are shifted to the right. As a result, the plates are held normally in locking position under the action of the springs c^4 , which tend constantly to move them to the left, so that to permit the operation of 5 the escapements the plates should be held to the right against the action of the springs. This is secured by providing the connecting link H^{31} and its extension H^{34} with set screws or abutments c^{13} which are arranged 10 to engage and actuate the plates as the link is moved upwardly and downwardly in effecting the unlocking and locking of the swinging frame G , respectively. Thus, as shown in Fig. 9, when the frame G is locked 15 in position an abutment c^{13} stands in engagement with the left end of the corresponding locking plate c , and holds it to the right in inactive position. When, however, the frame is unlocked, the upward 20 movement of the link H^{31} carries the abutment c^{13} upwardly therewith out of engagement with the locking plate, which is then shifted to the left by the spring c^4 , and thus caused to assume its locking position, see the 25 dotted lines in Fig. 9. When the frame G is relocked, the abutment c^{13} is carried downward by the movement of the link H^{31} , and, by its engagement with the inclined 30 end of the locking plate c , shifts the latter 35 to the right, causing it to resume its original or inactive position. In the present instance, the bottom edge of each plate c is formed with a depending flange c^{12} adapted to engage in notches in the rear upper corners of 40 the lips c^1 on the escapement actuating levers C^1 so as to become interlocked with the latter and positively hold them against pivotal movement. The general operation of the parts has been described before and need 45 not be repeated here. In both forms, the supplemental locking devices are moved automatically to active position when or before the frame G is swung forwardly, and the second form differs essentially from the 50 first only in the respect that the locking devices are also moved automatically to inactive position when the frame is restored. 55 Figs. 10 and 11 illustrate a modification of my invention. In this embodiment, the supplemental locking devices and associated parts before described have been dispensed with, and the escapements C and their co-operating rock shafts H have been modified so that the shafts may be moved to active 60 position even though one of the escapements should at the time occupy an improper or abnormal position. As seen in these figures, each of the escapement levers is of hook-shaped form at its rear end, so as to present 65 in its upper edge a recess C^a and an over-

hanging lip C^b ; and each of the rock shafts H is formed with a longitudinal groove h^2 which leaves at one side a longitudinal rib h^3 . As the parts are thus formed, when a rock shaft occupies an inactive position, its 70 groove h^2 overlies the rear ends of the escapement levers and permits the latter to be rocked freely in opposite directions to effect the release of the matrices (see Fig. 10). When, however, the shaft is in active position, its rib or solid portion h^3 overlies and 75 engages the upper edges of the overhanging lips C^b of the escapement levers and thus locks the latter against movement. This 80 form and arrangement of the escapements and the rock shafts is such that the latter may be moved to active position even if one or more of the escapements should be held in abnormal position, as so illustrated 85 in connection with the upper magazine in Fig. 10. In such event (see particularly Fig. 11) the rib h^3 of the rock shaft enters the recess C^a of the abnormally located escapement, and passes over the overhanging lips C^b on the remaining escapement levers, 90 holding the latter down against the action of their springs C^4 . In this way the caught escapement lever, instead of locking the rock shaft against rotation, as before, permits 95 its free rotation at all times. 95

The invention, therefore, consists broadly in the provision of locking means which will insure the locking of the escapements of all the magazines when the front plate is swung forwardly, and the mechanisms illustrated 100 are alike in the respect that each series of escapements is provided with a locking device so formed or arranged relatively thereto that it can be moved to active position even when one of the escapements is improperly 105 located. In the first two forms, this result is secured by the provision of a supplemental locking device which co-operates indirectly with the escapements, that is, through the medium of the pivoted actuating levers C^1 , 110 the latter being suitably formed so as to permit the locking device to be moved to its active position even though one of the escapements be caught; and in the last form, the rock shaft H and the escapements with 115 which it directly co-operates are modified, or changed from their ordinary construction, so as to permit the shaft to be rotated to active position when one of the escapements is caught. The last form also presents the 120 additional capability of insuring the proper locking of the escapements in changing back and forth between the two magazines, it being noted that the liability of the escapements becoming caught by improperly located matrices is present during this operation as it is when the front plate is swung 125 forwardly. 125

It is well known that in some machines of the class illustrated, the magazines may be 130

provided with locking devices to engage directly with the contained matrices to hold them therein, instead of engaging with the escapements as shown. In both cases, the 5 matrices are locked within the magazines, in the first directly, and the second indirectly. It will be apparent, therefore, that my invention comprehends both arrangements, it being the essential idea to insure 10 the locking of the matrices within the magazines before the escapements and their actuating members are disconnected. However, the use of the locking devices to hold the escapements against operation is preferable, possessing certain advantages which 15 would not obtain when they are arranged to coöperate directly with the matrices.

As is also well known, the locking devices may be variously modified in form or applied to many different classes of machines. 20 It is to be understood, therefore, that my invention has been shown merely in preferred form and by way of example and as applied to a particular style of machine, and obviously many modifications and alterations 25 therein and in its mode of application will suggest themselves to those skilled in the art without departure from its scope.

Having thus described my invention, its 30 construction and mode of operation, what I claim and desire to secure by Letters Patent of the United States, is as follows:

1. In a typographical machine, the combination of a magazine, a series of escapements therefor, and two distinct locking devices each coöperating with all of the escapements to hold them against operation.

2. In a typographical machine, the combination of a magazine, a series of escapements therefor, and two automatically operated locking devices each coöperating with all of the escapements to hold them against operation.

3. In a typographical machine, the combination of a matrix magazine, a series of escapements therefor, actuating members connected to the escapements, two distinct locking devices for the magazine each operative to retain all of the matrices therein, 45 and means for moving one or both of the locking devices to active position when the actuating members are disconnected from the escapements.

4. In a typographical machine, the combination of a magazine, a series of escapements therefor, actuating members connected to the escapements, two distinct matrix locking devices for the magazine, a movable frame carrying the actuating members, locking means for holding the frame in its operative position, and connections whereby the unlocking of the frame effects the movement of one or both of the matrix locking devices to active position.

5. In a typographical machine, the combination of a plurality of magazines, escapement mechanism for all of the magazines, a single series of actuating members connected to the escapement mechanism, matrix locking devices, one for each magazine, means whereby the movement of one of said locking devices to inactive position effects the return of another to active position, means for disconnecting the escapement mechanism and its actuating members, and automatic means for restoring the inactive locking device to active position when such disconnection is effected, with a supplemental matrix locking device for each magazine, together with mechanism for moving 80 said supplemental locking devices to active position when the escapement mechanism and its actuating members are disconnected.

6. In a typographical machine, the combination of a plurality of magazines, escapement mechanism for all the magazines, a single series of actuating members connected to the escapement mechanism, matrix locking devices, one for each magazine, means whereby the movement of one of the locking devices to inactive position effects the movement of another to active position, a movable supporting frame carrying the escapement actuating members, locking means for holding the frame in its operative position, and connections whereby the unlocking of the frame restores the inactive matrix locking device to active position, with a supplemental matrix locking device for each magazine, together with mechanism whereby the unlocking of the supporting frame effects the movement of the supplemental locking devices to active position.

7. In a typographical machine, the combination of a plurality of magazines each having a series of escapements and a movable locking device therefor, a common series of actuating members connected to the several series of escapements, means for disconnecting said actuating members from the escapements, and automatic means for restoring the several locking devices to active position when such disconnection is effected, with supplemental locking devices, one for each series of escapements, together with 110 mechanism for moving said supplemental locking devices to active position when the escapements and their actuating members are disconnected.

8. In a typographical machine, the combination of a plurality of magazines each provided with a series of escapements and a movable locking device therefor, a common series of actuating members connected to the several series of escapements, a movable supporting frame carrying the actuating members, means for locking the frame in its operative position, and connections

whereby the unlocking of the frame restores the escapement locking devices to active position, with supplemental locking devices, one for each series of escapements, and automatic means controlled by the unlocking of the supporting frame for moving said supplemental locking devices to active position.

9. In a typographical machine, the combination of a plurality of magazines, escapement mechanism for all the magazines, a single series of actuating members connected to the escapement mechanism, two movable matrix locking devices for each magazine, means for disconnecting the escapement mechanism and its actuating members, and automatic mechanism for moving one or both of the locking devices of each magazine to active position when such disconnection is effected.

20 10. In a typographical machine, the combination of a plurality of magazines, escapement mechanism for all the magazines, two movable matrix locking devices for each magazine, a single series of actuating members connected to the escapement mechanism, a movable supporting frame carrying the actuating members, means for locking the supporting frame in operative position, and connections whereby the unlocking of the frame effects the movement of one or both of the locking devices of each magazine to active position.

11. In a typographical machine, the combination of a magazine, a series of escapements therefor, actuating members connected to the escapements, means for connecting and disconnecting the escapements and their actuating members, two movable locking devices for the escapements, and automatic means for moving both the locking devices to active and inactive position as the escapements and their actuating members are disconnected and connected, respectively.

12. In a typographical machine, the combination of a plurality of magazines, escapement mechanism for all the magazines, a single series of actuating members connected to the escapement mechanism, matrix locking devices, one for each magazine, means whereby the movement of one of said locking devices to inactive position effects the return of another to active position, means for connecting and disconnecting the escapement mechanism and its actuating members, and automatic means for restoring the inactive locking device to active position when such disconnection is effected, with a supplemental matrix locking device for each magazine, together with automatic mechanism for moving the supplemental locking devices to active and inactive position as the escapement mechanism and its actuating members are disconnected and connected, respectively.

13. In a typographical machine, the com-

bination of a plurality of magazines, escapement mechanism for all the magazines, a single series of actuating members connected to the escapement mechanism, matrix locking devices, one for each magazine, means whereby the movement of one of the locking devices to inactive position effects the movement of another to active position, a movable supporting frame carrying the escapement actuating members, locking means for holding the frame in its operative position, and connections whereby the unlocking of the frame restores the inactive matrix locking device to active position, with a supplemental matrix locking device for each magazine, together with mechanism whereby the locking and unlocking of the supporting frame effects the movement of the supplemental locking devices to inactive and active position, respectively.

14. In a typographical machine, the combination of a magazine, a series of escapements therefor, a locking device to hold the escapements against operation, the said locking device being movable to active position when one of the escapements is in abnormal position, a series of actuating members connected to the escapements, means for connecting and disconnecting the escapements and their actuating members, and automatic mechanism for moving the locking device to active and inactive position as the escapements and their actuating members are disconnected and connected, respectively.

15. In a typographical machine, the combination of the magazine, the escapements C therefor, the pivoted actuating levers C¹ formed with the upstanding lips c¹, and the plate c coöperating with the lips c¹ and arranged to shift longitudinally and edgewise, in the manner and for the purpose described.

16. In a typographical machine, the combination of the magazine, the escapements C therefor, the pivoted actuating levers C¹ formed with the upstanding lips c¹ the plate c coöperating with the lips c¹ and arranged to shift longitudinally and edgewise, a spring for moving the plate in one direction, and positive means for moving it in the opposite direction, in the manner and for the purpose described.

17. In a typographical machine, the combination of a magazine, a series of escapements therefor, and a locking device to hold the escapements against operation, the said locking device and escapements being relatively formed to permit the locking device to be moved to active position when one of the escapements is in abnormal position.

18. In a typographical machine, the combination of a magazine, and a series of escapements therefor, with a locking device to hold the escapements against operation, the said locking device and escapements being

relatively formed to permit the locking device to be moved to active position when one of the escapements is in abnormal position, together with automatic means for effecting the movement of said locking device.

19. In a typographical machine, the combination of a magazine, a series of escapements therefor, a locking device to hold the escapements against operation, the said locking device being movable to active position when one of the escapements is in abnormal position, a series of actuating members connected to the escapements, means for disconnecting the actuating members from the escapements, and automatic means for moving the locking device to active position when such disconnection is effected.

20. In a typographical machine, the combination of a magazine, a series of escapements therefor, a locking device to hold the escapements against operation, the said locking device being movable to active position when one of the escapements is in abnormal position, a series of actuating members connected to the escapements, a movable supporting frame carrying the actuating members, locking means for holding the supporting frame in its operative position, and connections whereby the unlocking of the frame effects the movement of the escapement locking device to active position.

21. In a typographical machine, the combination of a plurality of magazines each provided with a matrix locking device, and means whereby the movement of one of said locking devices to inactive position effects the movement of another to active position, the said locking devices constructed and arranged so as to be movable to active position 40 when one of the matrices is improperly located in the corresponding magazine.

22. In a typographical machine, the combination of a plurality of magazines, each having a series of escapements and a locking device therefor, and means whereby the movement of one of said locking devices to inactive position effects the movement of the other to active position, the said locking de-

vices and the coöperating escapements being relatively formed so as to permit the movement of the locking devices to active position when one of the escapements is in abnormal position.

23. In a typographical machine, the combination of a plurality of magazines each having a series of escapements and a locking device therefor, the said escapements and locking device being relatively formed so as to permit the latter to be moved to active position when one of the escapements is in abnormal position, a series of actuating members connected to the escapements of the several magazines, means whereby the movement of one of the locking devices to inactive position effects the movement of the other to active position, means for disconnecting the actuating members from the escapements, and mechanism whereby such disconnection effects the return of the inactive locking device to active position.

24. A magazine containing columns of matrices and provided with two distinct locking devices each coöperating with the lowermost matrices in the several columns to retain them therein.

25. A magazine containing columns of matrices, and provided with a locking device to coöperate with the lowermost matrices in the several columns and hold them against escape, the said locking device being movable to active position in any position of the matrices in the magazine.

26. In a typographical machine, the combination of a magazine containing columns of matrices, a locking device to coöperate with the lowermost matrices in the magazine to retain them therein and movable to active position in any position of the matrices in the magazine and automatic mechanism for moving said locking device to active position.

In testimony whereof, I have affixed my signature in presence of two witnesses.

ALFRED W. F. GUEST.
